FEEDBACK AMPLIFIER CIRCUITS

Donald S. Bond, Philadelphia, Pa., assignor to
 Radio Corporation of America, a corporation of
 Delaware

Application July 30, 1938, Serial No. 222,092

2 Claims. (Cl. 179—171)

My invention relates to direct current amplifiers and more particularly to a direct current amplifier employing degenerative feedback.

I am aware that vacuum tube amplifiers have been designed for the amplification of direct current voltages and currents. I am aware also that various schemes have been suggested for maintaining stability notwithstanding variations in the supply voltages and differences in tube characteristics. Stability is a prime requisite in an amplifier which is to be used in making precision measurements. Stability must be had in the presence of changes which are caused by irregularities in the supply potentials.

One limitation on the accuracy of measuring equipment employing a direct current amplifier is the nonlinearity of the amplification characteristic with respect to the input voltage. If the amplification vs. input voltage curve can be made linear over a wider range, the utility of the instrument is greatly increased. Not only does its operation on any particular range become better, but also there is a uniformity of calibration over a larger number of different ranges.

I have found that, by employing a degenerative feedback system of the type which is described hereinafter, it is possible to construct an amplifier which has a large degree of independence of gain with respect to variations in the supply voltage and differences in tube characteristics over a wide range of input voltages.

It is an object of this invention to provide an improved direct current amplifier.

It is a further object of this invention to provide a direct current amplifier which is substantially independent of variations in supply potentials.

It is another object of this invention to provide a combination of means for obtaining degenerative feedback.

It is a further object of this invention to provide a direct current amplifier whose output voltage is a straight line function of the input voltage.

This invention will be better understood from the following description when considered in connection with the accompanying drawing. Its scope is indicated by the appended claims.

Referring to the drawing:

Figure 1 is a schematic drawing of one embodiment of my invention, and

Figure 2 is a graph showing the input voltage versus plate voltage characteristic of the device illustrated in Fig. 1 with and without feedback.

Referring to Figure 1: A pair of input terminals 1, 3 are connected, respectively, to the grids 5 and 7 of a pair of amplifier triodes 9 and 11. A pair of resistors 13 and 15 are connected in series between the grids 5 and 7. The midpoint of the resistors 13 and 15 is connected to the negative terminal of an anode supply battery 17, and also to both cathodes 19 and 21 through a bias resistor 23. A pair of feedback resistors 25 and 27 are respectively connected between the grids 5 and 7 and the anodes 29 and 31 of the vacuum tubes. A pair of output terminals 33 and 35 are respectively connected to the two anodes 29 and 31. A pair of plate load resistors 37 and 39 are connected in series between the anodes 29 and 31. The midpoint of the two last-named resistors is connected to the positive terminal of the anode supply battery 17.

It is evident from a study of the circuit diagram shown in Fig. 1 that the resistors 25 and 13 constitute a voltage divider circuit to impress a positive voltage on the grid 5. The value of this voltage is, of course, dependent upon the plate potential and the relative values of the two resistors. Resistors 27 and 15 likewise place a positive bias on grid 7. Consequently, a potential is impressed on the two grids 5 and 7 which is proportional to some predetermined fraction of the anode potential which exists on the two anodes at any particular instant.

In order to obtain a negative biasing potential for the proper operation of the tubes, a common cathode biasing resistor 23 has been employed. The value of this resistor is necessarily higher than is customary in order to produce a voltage which is sufficient to overcome the positive potential introduced by the voltage dividers mentioned above. The value of this resistor, for example, may be of the order of 50,000 ohms.

In the absence of an applied voltage the two tubes 9 and 11 draw equal anode currents and consequently have identical plate voltages. If a voltage is applied to the input terminals, one of the grids will become positive with respect to the other. Since the cathodes of the two tubes are connected together, an unbalanced condition results causing one tube to draw more plate current while the other tube reacts in the opposite direction to draw less plate current. As a result, a potential difference is established between the output terminals 33 and 35.

When grid 5 becomes more positive, the plate current of tube 9 increases and thereby reduces its applied anode voltage. As a consequence, the potential applied to the grid through the voltage dividing resistors 25 and 13 decreases

from its former value. The effect of this voltage is seen to be in a direction which tends to oppose the change due to the applied voltage. The feedback voltage is therefore said to be degenerative.

By a proper choice of resistors, the amount of feedback voltage can be made sufficient to reduce to any desired value variations in gain due to changes in the amplification factor of the vacuum tubes or due to variations in line voltage and other causes. For example, resistors 25 and 27 are of the order of 1.5 megohms. Resistors 13 and 15 are of the order of 1.2 megohms. As a result, the overall amplification is maintained uniform in the presence of varying factors which would normally affect the amplification of a vacuum tube amplifier. This is clearly shown by reference to Fig. 2.

Fig. 2 represents the operating characteristics of the amplifier shown in Fig. 1. The direct current voltage difference between the input terminals 1 and 3 is plotted against the direct current voltage difference between the output terminals 33 and 35. The curve entitled "without feedback" illustrates the amplification characteristic which is obtained by removing the feedback resistors 25 and 27 and readjusting the cathode bias.

The curve is linear only over a limited range. In contrast, a second curve is shown which was obtained from the device shown in Fig. 1 and is entitled "with feedback." The improvement is evidenced by the fact that the operation curve is linear over a range of output voltage which is nearly twice as great as that of the amplifier without feedback.

I have found experimentally that when feedback is employed the total cathode current remains essentially constant as the input voltage is varied. This is due to the fact that the increase in cathode current of one tube is substantially offset by a like decrease in the other tube. As a result, the negative grid bias remains constant. On the other hand, when feedback is not used, the cathode current rises rapidly as one tube reaches its cut-off value.

In making the comparison shown in Fig. 2, the grid bias in each case was adjusted to the point that gave the greatest degree of linearity of the input vs. output curve. Other bias adjustments could be made which give a higher gain over a limited range. For the optimum linearity, with and without feedback, the amplifier with feedback actually has higher gain than the amplifier without feedback. This is shown by the greater slope of the "with feedback" curve of Fig. 2.

While I have shown an amplifier having but

one stage, it is evident that further similar stages may be added. I also prefer the push-pull arrangement illustrated, but it is evident that the feedback method illustrated is applicable to a single tube direct current amplifier. It is to be noted that in the push-pull amplifier shown, the input and output connections are electrically symmetrical. Thus the normal tendency of a single stage amplifier to reverse the "sense" of the input voltage can be corrected by merely reversing the output connections. This is possible because of the electrical symmetry of the circuit.

I claim as my invention:

1. A direct current amplifier comprising two space discharge tubes each provided with a cathode, a control grid, and an anode, a common power supply for said tubes, a common cathode resistor connected between both of said cathodes and one terminal of said power supply, a pair of grid resistors respectively connected between each of said control grids and said one power supply terminal, means for applying an input current symmetrically to said pair of resistors so as to vary the voltages of said control grids in opposite directions with respect to said one power supply terminal in response to variations in said input current, and two feedback resistors, each connected between the anode and the grid of one of said tubes, cooperating with the respective grid resistors to provide a feedback path for each of said tubes whereby a portion of the output voltage of each of said tubes is applied to the control grid thereof to oppose variations in the voltage of said control grid.

2. A direct current amplifier comprising two space discharge tubes each provided with a cathode, a control grid, and an anode, a common power supply for said tubes, a common cathode resistor connected between both of said cathodes and one terminal of said power supply, a pair of grid resistors respectively connected between each of said control grids and said one power supply terminal, means for applying an input current symmetrically to said pair of grid resistors so as to vary the voltages of said control grids in opposite directions with respect to said power supply terminal in response to variations in said input current, and a pair of feedback resistors respectively connected between the anode and the control grid of each of said tubes, cooperating with the respective grid resistors to provide a voltage divider between the anode and the cathode of each of said tubes whereby a portion of the output voltage of each of said tubes is applied to the control grid thereof.

DONALD S. BOND.
